MOBILE FILM DISTRIBUTING MECHANISM

Peter Jay Massey, River Forest, Ill., and William F. Thiele and Bert F. Raprager, Wisconsin Rapids, Wis., assignors, by mesne assignments, of nine-tenths to Consolidated Water Power & Paper Company, Wisconsin Rapids, Wis., a corporation of Wisconsin, and one-tenth to Peter J. Massey, River Forest, Ill.

Application December 20, 1935, Serial No. 55,368

4 Claims. (Cl. 91—50)

This invention relates to improvements in a distributing mechanism for coating machines, printing presses and the like, the mechanism being characterized in that the axes of the rolls comprising the mechanism are all disposed in a common substantially horizontal plane.

It is a well known fact in industries where relatively heavy, long rolls are used for treating liquid, semi-solid or plastic materials, such as rolls used in the printing industry, that said rolls deflect due to the fact that they are supported at their ends and ordinarily no intermediate support is permissible or possible. Of course, the degree of deflection is greatest at the center of the rolls, if the rolls are symmetrical about their transverse centers, and said deflection is a function of the length of the rolls and their weight.

Frequently, rolls of this character are utilized to work, smooth and/or uniformly distribute a mobile material carried upon their surfaces, and in some cases a plurality of contacting rolls are used for this purpose, for instance, the ink distributing rolls of a printing press. In many instances it is of vital importance that the material carried on the surfaces of such rolls be closely controlled as to the thickness of the layer or film carried by said rolls and it is desired that said thickness be maintained uniform over the entire surface area of the rolls. Due to deflection, particularly in contacting or osculating rolls, this has heretofore been substantially impossible, since banks of such rolls have heretofore been disposed in a seemingly haphazard manner, for instance, the distributing rolls of a printing press which are usually disposed one above the other and also alongside of each other. It can readily be seen that if portions of the surface of one roll bear with different weights upon portions of an adjacent roll or rolls, the thicknesses of the films or layers upon the surfaces of said rolls will vary throughout different portions of said roll surfaces.

Our invention resides in the provision of a series of contacting distributing rolls wherein the detrimental effect upon surface carried films due to deflection of the rolls is reduced to a minimum. Our invention may be used in conjunction with printing presses or like mechanisms or operations, and is particularly adaptable for use in conjunction with a roll paper coating machine, as described in our copending applications for United States Letters Patent Serial No. 40,150 and No. 40,151, which are adapted to carry out the coating process described in the United States Patents to Peter J. Massey, Patents No. 1,921,368 and No. 1,921,369. Of course, although our present inven-

tion is described in its environment with a coating machine, it will be understood that, broadly, it may be used wherever a similar problem arises.

Other objects and advantages of our invention will be apparent from the accompanying drawing and following detailed description.

In the single drawing, a diagrammatic side elevational view of our device is illustrated as used in conjunction with a paper coating machine.

Referring in detail to the drawing, 1 indicates a coating machine with which our invention may be used. The machine comprises essentially two sets of substantially similar instrumentalities designated generally at 2 and 3 being the mechanisms for coating the upper and lower faces of a paper web 4 which passes continuously from the preliminary driers 5. The web 4 after being coated is passed to the final driers 6 wherein the web is dried to the desired degree. The upper mechanism 2 is suspended from a frame 7 which is supported by columns 8 and 9. The lower mechanism 3 may be mounted immediately beneath the mechanism 2.

The reference numeral 10 indicates a cylinder having a piston rod 11 projecting through the head thereof. Cylinder 10 may be mounted upon trunnions or bearings 12 whereby said cylinder may be rocked upon movement of piston rod 11. The end of piston rod 11 is connected to rod 13 which is journaled at its ends in opposite frame members 14. The frame members 14 are supported at their bottoms in oppositely positioned lugs or brackets 15, the supporting connection comprising a pivot 16 whereby the frame members may be rocked. Means (not shown) is provided whereby air or fluid under pressure may be introduced into the cylinder 10 either above or below the piston positioned therein, or, if desired, a vacuum may be established above or below the piston within cylinder 10. In either case the piston can be moved upwardly or downwardly in cylinder 10, which of course, causes cylinder 10 to rock about bearings 12 and frames 14 to rock about pivots 16. The purpose of so operating this mechanism will be hereinafter more fully described. A pair of standards 17 may be pivotally mounted on frame members 14, said standards being swingable or rockable about pivots 18. The upper ends of each of the standards 17 carry bearings 19 which support roll 20 between them. A pair of standards 21 may be rigidly mounted upon frame member 14, said standards carrying bearings 22 which support roll 23. Standards 17 and 21 may be connected at their upper ends by means of the adjustable capstan screw 24 whereby the

degree of proximity of roll 20 with respect to roll 23 may be controlled.

Referring particularly to the upper mechanism 2, the apparatus hereinbefore described is substantially duplicated. However, said apparatus is in inverted position and is carried by the frame 1. A cylinder 25 is carried upon bearings 26, piston rod 27 being slidably positioned through the head of the cylinder. Piston rod 27 is, in turn, connected to rod 28 at its end which is carried by the frame members 29. Frame members 29 are pivotally secured to lugs 30 upon each side of the machine which, in turn, are carried by frame 1.

Standards 31 and 32 are mounted in spaced relationship upon each frame member 29, said standards carrying bearings 33 and 34 respectively between which rolls 35 and 36 are mounted. The outer ends of standards 31 and 32, in this case, 20 the lower ends, are adjustably tied together by means of screw 37 whereby the degree of proximity of rolls 35 and 36 may be controlled. Rolls 20 and 23 and rolls 35 and 36, hereinafter referred to as fountain or gate rolls, are adapted to carry in their respective nips a quantity of liquid or semi-liquid coating material which is delivered therefrom through appropriate agencies through the coating rolls, all of which will be hereinafter described. Of course, it is to be understood that 30 the rolls 20 and 23 and 35 and 36 may be utilized in conjunction with other materials than coating material since the described arrangement merely serves as a source of supply for the distributing mechanism hereinafter to be described.

All of the rolls 20, 23, 35 and 36 are preferably of the same over-all diameter and are preferably separately driven. In operation, rolls 23 and 36 are driven counter-clockwise and rolls 20 and 35 are driven clockwise. Rolls 23 and 36 are adapted 40 to carry a film of desired thickness, of coating material which is adapted to be transferred to rolls osculating therewith hereinafter described. Obviously, in utilizing a machine such as herein described, it is desirable to apply different 45 types of coating material and different weights or quantities of coating to the web. In our machine, such control can primarily be obtained by means of the gate rolls 20, 23, 35 and 26. To exercise such control in addition to the proper 50 manipulation of capstans 24 and 37 which control the contiguity of each pair of rolls, said rolls are adapted to be driven at different peripheral speeds, that is, rolls 20 and 35 may be driven at a different speed than rolls 23 and 36. It is 55 preferred that the drive of rolls 23 and 36 but such as to drive said rolls from a speed equal to the speed of the rolls from which the film of coating is transferred to a speed of approximately $\frac{1}{4}$ as much. Rolls 20 and 35 are driven over a maximum 60 range of speed preferably from one revolution a minute to full speed corresponding to the maximum speed of rolls 23 and 36.

In the lower mechanism the film of coating material is transferred from roll 23 to the distributing roll 38 which revolves in a clockwise direction. The film is transferred therefrom to distributing roll 39 which revolves in a counter-clockwise direction, thence to roll 40 which revolves clockwise. From roll 40 the film is transferred to 65 form rolls 41 and 42, both of which revolve in a counter-clockwise direction. Form rolls 41 and 42 transfer the film to coating roll 43 which revolves in a clockwise direction and by which the film is applied to one surface of the web 4.

In the upper mechanism 2, the film of coating

material carried upon the surface of roll 36 is transferred to the surface of roll 44, which revolves in a clockwise direction. From roll 44 the film of coating material is transferred to roll 45 which rotates in a counter-clockwise direction. Roll 45 passes the film to roll 46 which revolves in a clockwise direction. Roll 46 transfers the film of coating material to the surface of roll 47 which rotates in a counter-clockwise direction. From roll 47 the film is passed to rolls 48 and 49, both of which revolve in a clockwise direction. The form rolls 48 and 49 pass the film from their surfaces to the surface of the upper coating roll 50 whereby said film is applied to the upper surface of web 4 simultaneously with the 15 application of a similar film to the lower surface thereof by roll 43.

Rolls 43 and 50 revolve at the same peripheral speed which is equal to the linear speed of web 4. In the lower mechanism 3, rolls 38, 39, 40, 41 and 42 all revolve at the same peripheral speed as roll 43 and in the upper mechanism 2 rolls 44, 45, 46, 47, 48 and 49 revolve at the same peripheral speed as coating roll 50. It will be noted that all of the rolls comprising the lower mechanism 3 25 with the exception of the form rolls 41 and 42 have their axes disposed in substantially the same horizontal plane. Similarly all of the rolls comprising the upper mechanism 2 with the exception of the form rolls 48 and 49 have their axes disposed in a common horizontal plane. In transferring the films of coating material from the coating rolls 43 and 50, the thickness of said film must be controlled to a fine degree of accuracy. The film in passing from roll to roll throughout 35 the upper and lower mechanism is worked and smoothed by such passage and such rolls must consequently be carefully adjusted with respect to their contiguity. It is well known that members of relatively great weight such as the rolls herein used being supported only at their ends deflect 40 due to their weight. By disposing substantially all of the rolls in a common horizontal plane, the deflection of all of said rolls is in the same direction and a film of uniform thickness may be carried throughout the entire surface of each of the rolls. This is a very important feature of our invention in view of the fact that the films of 45 coating material or ink applied to the web to be coated or printed must be applied in the uniform manner. Consequently said film must be prepared with the highest degree of accuracy and care, particularly with respect to its thickness and 50 distribution.

The distributing rolls comprising the upper 55 and lower mechanism are all of different diameters, that is, rolls 38, 39 and 40 have different diameters and rolls 44, 45, 46 and 47 are of different diameters. It can readily be seen that inasmuch as the peripheral speeds of all of said rolls 60 are equal the fact that the diameters are different prevent the surfaces of adjacent rolls from rigidly contacting along the same line. By this provision the surfaces of the rolls are maintained in uniform condition and ridges will not be formed 65 upon the ink or coating material carried upon the surfaces of said rolls.

Roll 38 is carried by bearings 51 which, in turn, are carried by standards 52 positioned upon each side of the machine. Standards 52 are pivotally mounted upon lugs 53. Each of the standards 52 is provided with upward extensions 54 which carry guides 55. A bearing block 56 is slidably positioned in said guides and may be adjusted upwardly or downwardly so as to bring 70

roll 57 carried by said bearings into desired position with respect to roll 38. Roll 57 is an idler roll and is driven only by means of its contact with roll 38. Roll 57 in so contacting roll 38 5 assists in working and smoothing the film of ink, coating material or the like, carried by roll 38.

Roll 39 is carried at each of its ends in bearings 58 which, in turn, are carried at the upper ends of standards 59 pivotally mounted upon lugs 60. In the case of both rolls 38 and 39, conventional means (not shown) is provided for oscillating said rolls longitudinally simultaneously with their rotation which action further assists in working and smoothing the film carried upon 15 their peripheral surfaces.

Roll 40 is carried by bearing 61, which in turn is mounted upon standards 62, positioned at each side of the machine, said standards being pivotally supported upon lugs 63.

20 Roll 42 is carried by bearings 64 which are slidably positioned in guides 65, said guides being carried by standards 66 which are pivotally mounted at their lower ends upon lugs 67. Bearings 64 may be moved upwardly or downwardly 25 thereby moving roll 42 upwardly or downwardly. Roll 41 is carried by bearings 68 which, in turn, are carried by standards 69 also pivotally mounted upon lugs 67. Standards 69 comprise a frame which embraces a portion of standards 66 and the 30 center line of bearings 64 can be changed with respect to the center line of bearings 68 by means of set screws (not shown) threadedly positioned upon opposite sides of each of the standards 69 and adapted to bear upon the guide portion of 35 standards 66.

Rolls 44, 45, 46, 47, 48 and 49 are mounted in substantially the same manner as rolls 38, 39, 40, 41 and 42. To simplify the description only those portions of the upper mechanism associated 40 with said rolls which differ from the lower mechanism will be described. In view of the fact that rolls 44 to 49 inclusive are positioned above the passing web 4, said rolls are disposed upon suspended supports, all of said supports 45 being pivotally connected to the frame 1. Frames 14 and standards 52 are connected together by means of an adjustable capstan screw 70 and in a similar manner standards 52, 59 and 62 are adjustably connected. The same arrangement 50 is utilized in the upper mechanism 2 and is described in detail in our co-pending applications, Serial No. 40,150 and No. 40,151. Similar adjustments are provided between roll 40 and rolls 41 and 42, said adjustments comprising capstan 55 screws 71. Rolls 41 and 42 are additionally adjustably positioned with respect to roll 43 by means of the capstan arrangement 72.

Coating roll 43 is mounted upon bearings 73 which, in turn, are supported by standards 74. 60 Roll 50 is mounted upon bearings 75 which are pivotally secured as at 76 to standard 77 mounted upon frame 1. A rod 78 is connected to an extension 79 of bearing 75, said rod being adapted to raise or lower bearing 75 so as to raise or 65 lower roll 50 with respect to roll 43. This construction, however, is particularly adapted to coating machines and is not strictly essential to our present invention. The web 4 after passing between rolls 43 and 50 is coated upon each surface 70 thereof and is subsequently passed between air conduits 80 and 81 which are adapted to direct air under pressure into contact with the coated surfaces in order to dry the same. The web 4 may then be directed over roll 82 and thence over the 75 rolls comprising drier 6. In passing around the

first drier roll air conduit 83 is adapted to discharge blasts of air under pressure into contact with the outer surface of the web. This mechanism is clearly described in our co-pending application Serial No. 40,150 and No. 51,740. A roll 5 mounted upon bearings 85 which, in turn, are carried by standards 86 may be adapted to contact roll 43 and is adapted to clean said roll after its contact with web 4, roll 84 being provided with a doctor blade 87. An arm 88 extends outwardly from standard 86 and is connected to piston rod 89 which is slidably positioned in the head of cylinder 90. By introducing compressed air or other fluid under pressure into the lower portion of cylinder 90, standard 86 may be rocked 10 about its pivotal connection 91 so as to bring roll 84 into contact with roll 43. The upper mechanism is a duplication of that herein described. 15

As is particularly described in our copending application Serial No. 40,151, all of the standards comprising the lower bank may be rocked clockwise by supplying fluid under pressure to the lower portion of cylinder 10. In this manner all of the rolls are brought into contiguous relationship. Similarly, by supplying fluid under pressure to the upper portion of cylinder 25 all of the standards comprising the upper mechanism will be rocked counterclockwise, bringing the respective rolls into operative contact. By supplying fluid under pressure to the opposite ends of the cylinders 10 and 25 the respective rolls may be separated, the standards being tied together by the capstan screws. 30

As has been hereinbefore described, the salient feature of our present invention resides in the disposition of the axes of the various rolls constituting the distributing mechanism in one substantially horizontal plane whereby the effect of the deflection of said rolls upon films carried upon the surfaces thereof is reduced to a minimum. 40

We claim as our invention:

1. In combination, a plurality of juxtaposed rolls having their surfaces closely adjacent each other and their axes in parallel relationship, said rolls being supported adjacent their ends and being of such a length and weight as to deflect substantially at their longitudinal centers, the axes of said rolls being disposed in substantially the same horizontal plane whereby deflection of said rolls is negligible in changing the uniform clearances between adjacent roll surfaces, and means for applying a mobile coating material to one of said rolls whereby said material is transferred from roll surface to roll surface in the form of a relatively thin film of uniform thickness suitable for the coating of paper. 50

2. A mechanism for distributing and smoothing a mobile coating material to form a relatively thin film of relatively uniform thickness which comprises, a pair of horizontally juxtaposed gate rolls adapted to carry a quantity of mobile coating material in their nip, a plurality of serially aligned distributing rolls, one of said distributing rolls being in film transferring relationship with one of said gate rolls whereby said mobile coating material is transferred from said gate roll to said adjacent distributing roll, said distributing rolls being supported at their ends and being of a length and weight which causes substantial deflection, all of said rolls having their axes in substantially the same horizontal plane whereby deflection of said rolls has negligible effect in changing the uniform clearance between adjacent rolls. 70

3. A mechanism for distributing coating material comprising, a pair of juxtaposed gate rolls adapted to carry a quantity of mobile material in their nip, a plurality of serially aligned distributing rolls disposed in film transferring relationship to one of which distributing rolls said mobile material is transferred from one of said gate rolls, said distributing rolls being supported at their ends and being of a length and weight which would cause substantial deflection, all of said rolls having their axes in substantially the same horizontal plane whereby deflection of said rolls has negligible effect in changing the uniform relatively small clearance between adjacent rolls.

4. In combination, a plurality of serially aligned rolls disposed with their adjacent surfaces in sufficiently close proximity to transfer

a film of coating material from roll surface to roll surface, said rolls being supported at their ends and being of such length and weight as to deflect substantially at their longitudinal centers, the axes of said rolls being so disposed as to remove the direction of said deflection substantially 90° from a plane common to the respective lines of film transference whereby said deflection is negligible in changing the uniform clearances between adjacent roll surfaces, and means for applying a mobile coating material to the first distributing roll of said series whereby said coating material is transferred from roll surface to roll surface in the form of a relatively thin film.
